LINT REMOVER

Erwin Howard Wilbrecht, Shadow Mountain, Fairway
Cottages 4A, Palm Desert, Calif.

Filed Feb. 19, 1965, Ser. No. 83,906

Term of patent 14 years

(Cl. D9—2)

FIG. - 1

FIG. - 2

FIG. - 3

FIG. - 4

FIG. 1 is a perspective view of a lint remover in accordance with my new design;

FIG. 2 is a front view of the lint remover of FIG. 1;

FIG. 3 is an end view of the lint remover of FIG. 1 showing the end which is not visible in FIG. 1; and

FIG. 4 is a top view of the lint remover of FIG. 1.

I claim:

The ornamental design for a lint remover, as shown and described.
